UNITED STATES PATENT OFFICE.

GUY B. FITZ, OF AUBURN, MAINE, ASSIGNOR TO FITZ-EMPIRE DOUBLE PIVOT LAST COMPANY, OF AUBURN, MAINE, A CORPORATION OF MAINE.

BLOCK LAST.

Application filed July 16, 1919. Serial No. 311,219.

To all whom it may concern:

Be it known that I, GUY B. FITZ, a citizen of the United States, residing at Auburn, in the county of Androscoggin and State of Maine, have invented certain Improvements in Block Lasts, of which the following description, in connection with the accompanying drawings, is a specification, like reference characters on the drawings indicating like parts in the several figures.

This invention relates to boot and shoe lasts and in particular to block lasts. It has been found advisable to unite the instep block to the main body of the last by a connection of some kind, in order to avoid loss or misplacement of the block. This connection has to be loose and flexible in order to permit ready withdrawal of the block and has heretofore been in the form of a cord having its ends fastened to the two last parts. This cord, however arranged relatively to the last, is in the way, is hard to manage, gets caught between the last parts and prevents their proper assembly, and portions of it are often caught between the last and the jack and cut.

It is the object of the present invention to provide an instep block connection which will avoid the above and other disadvantages.

An important feature of the invention consists in a connection receiving channel lying entirely within the last, the external surface of the last being normal.

Another feature resides in a flexible connection comprising a plurality of freely pivoted members. This connection is illustrated as a metallic chain, the weight and perfect flexibility of which make its manipulation very simple and convenient.

These and other features of the invention, including certain details of construction and combinations of parts, will be understood from the following description of a preferred embodiment of the invention, selected for purposes of illustration and shown in the accompanying drawings in which:—

Fig. 1 is a perspective view of the last showing the block detached;

Fig. 2 is a sectional view of the last and block assembled.

The instep block 10 is of ordinary shape,

and is held in position by the pin 12 and the sliding bolt 14, which respectively engage holes 16, 18. These features are all of ordinary construction.

One of the last parts, preferably the main body, has a channel 20 formed along the joint surface, extending substantially the length of the connection desired between the block and the main body of the last. A suitable anchoring means, illustrated as a screw eye 22, is inserted at one end of this channel; another eye 24 is inserted in the unchanneled last part near the other end of the channel, and these eyes are united by a flexible connection, preferably a metallic chain 26.

This chain is more perfectly flexible than any cord of even approximately equivalent strength and can be placed in and will fall to the bottom of the channel 20 without any manipulation, or repeated trials. The pin 12 is offset from the channel, so that the chain will not become tangled with the pin.

An important advantage of the illustrated construction resides in the freedom of the outside surface of the last from holes related to the connection. All parts of the connection are entirely concealed, and the surface of the last is perfectly normal. There is no projecting portion of the connection to get in the way or to be injured or cut by the use of the last.

Having described my invention, what I claim as new and desire to secure by Letters Patent of the United States is:—

1. A block last having a connection receiving channel between the last parts and lying entirely within the last, and a chain connection lying in said channel, entirely concealed when the last is assembled and anchored to the last parts, the external surface of the last being unbroken by said connection.

2. A block last having a channel in the main body and a metallic chain fastened to the body and the block near the ends of the channel, and arranged to drop under the action of gravity into the channel when the last is assembled.

In testimony whereof I have signed my name to this specification.

GUY B. FITZ.
